UNITED STATES PATENT OFFICE.

ROBERT T. BENEFIELD, OF INDIANAPOLIS, INDIANA.

PERMUTATION LOCK FOR AUTOMOBILES.

Application filed July 9, 1921. Serial No. 483,889.

To all whom it may concern:

Be it known that I, ROBERT T. BENEFIELD, a citizen of the United States, residing at Indianapolis, in the county of Marion and State of Indiana, have invented new and useful Improvements in Permutation Locks for Automobiles, of which the following is a specification.

The object of this invention is to provide means between the carburetor of an internal combustion engine and the explosion cylinders thereof, of a motor car, for cutting off the gas mixture when the car is parked, to prevent thieves and unwarranted persons from driving the car.

A further object is to provide means to insure that said gas mixture cut-off means is set to cut-off the gas mixture when the engines are stopped in parking the car. 20 Otherwise, the element of human carelessness will cause the closing of the gas mixture cut-off to be neglected, thereby defeating the objects of the invention, and, inasmuch as the drivers of cars are trained to open the 25 battery circuit when they park their cars to keep their batteries from becoming exhausted, one of the principal objects of this invention is so to connect the gas mixture cut-off with the battery circuit that the opening of the battery circuit must be attended by cutting off of the gas mixture supply to the engine, the latter being preferably cut-off before the battery circuit is opened.

I accomplish the above and other objects 35 which will hereinafter appear by the mechanism illustrated in the accompanying drawing in which—

Fig. 1, is a side elevation of a typical internal combustion engine applied to an automobile and embodying my invention. Fig. 2 is a section on the line 2—2 of Fig. 4, showing the housing in top plan view. Fig. 3, is a view on the line 3—3 of Fig. 4 looking in the direction of the arrows, with the mechanism in closed battery circuit and the gas mixture valve opened. Fig. 5, is a section on the line 5—5 of Fig. 4, looking in the direction of the arrows. Fig. 6, is a view like Fig. 3, but on a larger scale, with the operative mechanism in open battery circuit and the gas mixture valve closed. Figs. 7 to 10, inclusive, show disks of the permutation lock separated and in top plan view.

Like characters of reference indicate like parts in the several views of the drawings.

In Fig. 1, of the drawings the carburetor 11 is supplying a gas mixture through intake manifold 12 which is the hydrocarbon mixture supply pipe to the cylinders of the engines, and the cut-off valve is introduced 60 in the stem of the manifold 12. Its internal mechanism which includes a circuit make-and-break for the ignition to be hereinafter described, is operated by a shaft 13, which is connected with a dial shaft 14, by an extension shaft 15. The latter has universal joints 16 where it connects with the shafts 13 and 14 to make the out-of-line transmission between the latter. The dial-shaft passes through the dash 17 and terminates with a 70 milled knob 18 by which the shaft is rotatively manipulated in either direction. Fixed on the shaft 14 is a dial-plate 19, with the usual numbered graduations for a permutation lock, by which the shafts are turned to make or break the combination, in the usual manner, for which the combination is set.

The housing in which shaft 13 is mounted is cylindrical, the shaft being mounted in 80 the axis of the cylinder in a boss 20, on the upper closed end of the cylinder. The opposite end of the cylinder has a lateral outside plate-extension 21 which mates with a plate 22, also extended to form a closure 85 for the otherwise open lower end of the cylinder. The plate extensions 21 and 22, in contact with each other, are passed at right angles through the intake manifold stem or pipe 12 by cutting the latter if there is no 90 available joint suitable for the purpose, and formed through the two plates are registering openings 23 which register with the bore of the manifold pipe and substantially conform therewith in size. The plate 21 has 95 a suitable recess 24, in which is a gate-valve 25, adapted in one position to close the openings 23 and thereby shut off the flow of gas mixture from the carburetor to the engines. The shape of the recess 24 is such as to 100 properly guide the valve. The latter has a stem 26, the outer end of which is pivotally connected with a post 27, seated in a metal plate 28. The latter is fixed to a sleeve 29 (see Fig. 4), loosely mounted on the shaft 13. Fixed on the lower end of the shaft 13 is 105 a disk 30 between which and the plate 28 are a series of permutation disks to cooperate with suitable mechanism, hereinafter described, whereby under certain combi- 110

nations of said disk the manually rotated shaft 13 will move plate 28 and post 27 to side the gate-valve 25 in its recess 24.

As one of the principal objects of this invention is to cut off the gas mixture when and only after the ignition circuit is broken, I will now explain the circuit make-and-break mechanism and its connection with the gate-valve operating mechanism.

10 Supported upon the plate 28 is a circular disk 31, of fibre or other electric non-conductor, which supports a metal conducting ring 32 concentric with shaft 13 and about midway of the diameter of the plate 28.

15 This conductor 32 is in permanent electric connection with a metal brush 33, attached to a binding-post 34, supported by but insulated from the closed end of the cylindrical housing, as shown best in Fig. 4. The post 34 is wired to the usual coil in coil-box 35 on the dash of the car (see Fig. 1), which is connected with the usual ignition mechanism (not shown) in the engine.

20 Mounted enough further out on disk 31 to prevent electrical leakage from ring 29, is an annular segment 36, which lacks about 40° of making a complete circuit. Approximately 180° of this segment is on the same side of disk 31 as ring 29, and the rest of it is 25 on the opposite side of the disk to which it is carried by bending it through a radial slit in the disk. This end on the underside of disk 31 is bent down at right angles to form the member 37, which supports a contact member 38.

30 A ring 39 of insulating material is loosely mounted on the sleeve 29. It has a radial outwardly extended arm 40, to which a metal segment 41 is riveted. An end of this arm is bent down at right angles to form 35 the member 42, which supports a contact member 43 that is adapted to be brought into contact with the member 38 by an oscillatory movement of the arm 40. The opposite end of the segment 41 makes rubbing 40 contact against a radial metal arm 44, the inner end of which is electrically connected with the conductor-ring 32. The closed end of the cylindrical housing, previously referred to, also supports two more binding- 45 posts 45 and 46, which are respectively wired to a magneto and to a battery. These posts in turn support brushes 47 and 48, which, by the location of the posts are spaced less than 180° apart, whereby they 50 may both be simultaneously in electric contact with the conductor-segment 36 of the adjacent upper side of the disk 31 (see Fig. 5), or either one of said brushes may be in said contact and the other not, or they may 55 both be out of contact, according to the position of disk 31, and the electric circuit, which must include ring 32, is made or broken by contacting or separating the members 38 and 42.

60 The position of the arm 40 determines

this condition, which, in turn, is controlled by mechanism influenced by a leaf spring 50. The latter is pressed against the post 27 and further against a post 51 supported by the plate 28. Pivotaly mounted on the post 70 27 is a T-shaped plate 52. The small or foot end of the stem is the pivotal end and the opposite or head end 53 is bent down at right angles with the stem. The shape of this head provides a projecting portion on each side of the stem. That part toward the inside of the housing is normally pressed by the spring 50 against the edges of three permutation disks 54, 55 and 56 75 loosely mounted on sleeve 29. An arm of the spring passes through a slot in the head 53. The disks have notches as shown in Figs. 7, 8 and 9, and so long as these notches are not opposite the head 53, the latter is held in the position shown in Fig. 6, so the outer projection of said head will contact the end of a concentric rib 54 on the inner wall of the cylindrical housing.

80 Pivoted on the post 51, is a lever having an arm 55 with a rounded end which enters a corresponding notch in the periphery of the ring 39, substantially in a line from the center of the post 51 to that of the shaft 13. This lever has a second arm the end of which is turned down to form a head 56 assembled close to the head 53 but only long enough to contact the two upper disks 54 and 55. The same lever has a third arm in opposite direction from the second one, which terminates with a hook 57 which forms a bearing for spring 50 extended.

85 The permutation disks 54, 55 and 56 each have pins 60 in the usual manner for contact with each other in working the combination and as a check and aid in setting the combination, the outer end of boss 20 is beveled and graduated to co-operate with an index pin 61 carried by the shaft 13.

90 The position of the several parts of my device when the circuit is broken and the gas-valve closed is substantially as shown in Fig. 6, and with the parts as therein shown, the operation in closing the circuit and opening the valve is as follows:

95 The counters are turned by manually rotating the knob 18, and through it shaft 13, to bring the notches of the disks 54 and 55 together opposite the head 56, whereupon the tension of the spring 50 against the head 57 rocks the lever on its pivot 51 and causes 100 the arm 55 to rotate the ring 39, thereby bringing the contact member 43 carried by the arm 40 into contact with the member 38. This closes the electric circuit so the battery and magneto are connected ready to fire 105 as soon as the proper gas mixture is admitted to the engine cylinders; but the intake manifold is closed by the gate-valve 25. The latter cannot open because the head 53 is 110 against the end of the rib 54 from which 115

120 125 130

it cannot release until the notch in disk 58 comes opposite the head 53. Thereupon, the head 53 enters the notches of all of the permutation disks and being then out of contact with rib 54 the plate 28 and post 27 to which the stem of the gate-valve 25 is pivoted, is moved to the position shown in Fig. 3, in which the manifold pipe is open and the electrical circuit is closed.

10 In the reverse operation, the electric circuit is opened before gas is completely cut-off. This is done for a purpose, as the operator learns not to leave his car without breaking the battery circuit, because he 15 knows that to leave the circuit closed will exhaust the battery and stop all further use of the car until the battery has been renewed. He is sure to remember to break the electric circuit, and by doing that with my invention installed he is sure to close the gate-valve and cut-off the gas supply, which without being connected with the electric mechanism might be forgotten.

While I have here shown and described the preferred form of my invention, it is obviously capable of many variations in construction and material and I therefore do not desire to be limited unduly or any more than is required by the appended claims.

30 What I do claim as new and wish to secure by Letters Patent is:—

1. The combination with an internal combustion engine, an intake manifold for the engine and an electric circuit system, of a valve movable to positions to open and to close said manifold, a shaft, a plate loose upon said shaft, a connection between said plate and said valve for operating the valve by the plate, means for rotating said shaft, devices controlled by said shaft for causing said plate to actuate said valve to open and to close said manifold, circuit make and break elements supported in part by and operated by said plate for closing and opening said circuit, and means for causing said

elements to open said circuit before said plate moves said valve completely to closed position.

2. The combination with an internal combustion engine, a carburetor, a communication from the carburetor to the engine, and an electric circuit system, of a valve movable to position to open and to close the communication between the carburetor and the engine, a shaft, a plate loose upon said shaft, a connection between said plate and said valve for operating the valve by the plate, means for rotating said shaft, devices controlled by said shaft for causing said plate to actuate said valve to open and to close said communication, circuit make and break elements supported in part by and operated by said plate for closing and opening said circuit, and means for causing said elements to open said circuit before said plate moves said valve completely to closed position.

3. The combination with an internal combustion engine, a gas intake for the engine, and an electric circuit system, of a valve movable to positions to open and to close said intake, a housing, a shaft extending into the housing, a plate loose upon said shaft inside the housing, a connection between said plate and said valve for operating the valve by the plate, means for rotating said shaft, devices controlled by said shaft for causing said plate to actuate said valve to open and to close said intake, circuit contact members supported by the housing, circuit make and break elements supported and operated by said plate for cooperation with said contact members in opening and closing said circuit, and means for moving said elements out of position to cooperate with said members after said valve has moved partially to closed position and before the valve is entirely closed.

Signed at Indianapolis, Indiana, this the 7th day of July, 1921.

ROBERT T. BENEFIELD.
